UNITED STATES PATENT OFFICE.

OSROE A. CLARK, OF NEWARK, NEW JERSEY.

BLADE.

967,500.

Specification of Letters Patent. Patented Aug. 16, 1910.

Application filed August 12, 1909. Serial No. 512,499.

To all whom it may concern:

Be it known that I, OSROE A. CLARK, a citizen of the United States, residing at Newark, in the county of Essex and State of New Jersey, have invented certain new and useful Improvements in Blades; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

This invention relates to an improved blade for use in safety razors, and is particularly designed for those razors in which the blade is flexed or bent parallel with its cutting edges, and held in a holder in this curved position while used for shaving. The blade is made so that it bends easier than the former style of blades, and also is less apt to crack or break when bent.

The invention is illustrated in the accompanying drawings, in which—

Figure 1 is a face view of a blade made after my new design of blade, and Fig. 2 is a section taken between one end, of the blade shown in Fig. 1, and the slot in the blade, but slightly enlarged.

The blade is made of steel, and has the cutting edges 11 arranged on parallel sides. The blade is of the form known as "wafer" blades and is designed to be bent or curved transversely, so that the cutting edges are at an angle to each other instead of being in line. When so bent, blades have been known to break frequently, and the loss on this account is considerable. The blades are of hard metal and are brittle, the greatest strain coming about at the longitudinal center of the blade where the contraction on one surface and the tension on the opposite surface is greatest.

I provide my blade with a thinned or more flexible portion 12, which can be placed in the blade when it is made or can be put in afterward, by grinding, for in-

stance. In blades of any kind this thin or more flexible part made integral with the rest of the blade can be utilized to facilitate the bending of the blade. This form of blade with the thinned portion can be made solid or supplied with a perforation or perforations, as at 13, according to the make of razor in which it is to be used.

Having thus described my invention what I claim is:—

1. A blade made of a single sheet of flexible material having parallel cutting edges, and having a thinned portion extending through it between the cutting edges.

2. A blade having parallel cutting edges and having a thinned portion extending between, and substantially parallel to its cutting edges.

3. A blade formed of flexible metal having parallel cutting edges and with an integral but more flexible portion extending through it between the cutting edges, the more flexible portion being thinner than the rest of the blade.

4. A blade formed of flexible metal having parallel cutting edges, said blade having a strip more flexible than the body portion of the blade, the strip being integral with the body portion and parallel with, and between, the cutting edges the more flexible strip being thinner than the blade proper.

5. A flexible razor blade with cutting edges on opposite sides having a thinned portion between the cutting edges to make the blade more flexible.

6. A flexible razor blade having parallel cutting edges, said blade being provided with a ground portion on both sides to thin the blade between the cutting edges.

In testimony, that I claim the foregoing, I have hereunto set my hand this 11th day of August 1909.

OSROE A. CLARK.
